J. E. TRAVER,
TOE PORTION OF BOOTS AND SHOES,
APPLICATION FILED JUNE 21, 1915.

1,245,534.

Patented Nov. 6, 1917.

WITNESS:

S. H. Taylor.

INVENTOR
Jay E. Traver.

BY
Ernest Hopkinson
HIS ATTORNEY

UNITED STATES PATENT OFFICE.

JAY E. TRAVER, OF NAUGATUCK, CONNECTICUT, ASSIGNEE TO THE GOODYEAR'S METALLIC RUBBER SHOE COMPANY, A CORPORATION OF CONNECTICUT.

TOE PORTION OF BOOTS AND SHOES.

1,322,202.

Specification of Letters Patent.

Patented Nov. 6, 1917.

Application filed June 21, 1915. Serial No. 35,249.

To all whom it may concern:

Be it known that I, JAY E. TRAVER, a citizen of the United States, and a resident of Naugatuck, county of New Haven, and State of Connecticut, have invented certain new and useful Improvements in the Toe Portions of Boots and Shoes, of which the following is a full, clear, and exact description.

10 This invention relates to shoes and has reference more particularly to that portion of the shoe commonly known as the cap.

In constructing shoes it is customary to form a seam at the tip which seam in addition to uniting two contiguous members of the shoe upper together, also produces an ornamental effect. The present invention has for an object to produce at the toe of the shoe an ornamental tip without forming any 20 seam, but on the contrary, permitting of the use of a continuous section of material over the toe and instep portion of the shoe, where hitherto, as above stated, it has been necessary to use separate pieces.

25 The invention will be readily understood from the following description taken in connection with the accompanying drawing, in which

Figure 1 is a fragmentary perspective view of the toe portion of a shoe, embodying the invention, partly broken away;

Fig. 2 is a detail sectional view of the invention.

Fig. 3 is a perspective view of the toe box and cord.

For the purpose of illustration only, I have shown the invention as applied to a shoe of the so-called "tennis" type, that is, a shoe embodying a fabric upper and a rubber sole. However, the invention is not limited to this particular type of shoe, as the same may be used in connection with a shoe having a leather upper, without departing from the spirit or sacrificing any of the advantages of the invention.

Referring now to the drawing, the shoe is shown to comprise an upper 10, embodying a lining 11 and a cover 12, both of fabric, these parts being turned inwardly at the 50 edges and secured between an insole 13 and and outsole 14, as shown. In this instance the outsole 14 is of rubber, the same being cemented or otherwise secured to the upper and insole.

55 For stiffening the toe portion of the up-

per, a toe box 15 is provided, the same in this instance being formed of comparatively stiff material, such as that material commonly known as "rag stock" in the rubber shoe industry. This toe-box is interpolated between the lining 11 and cover 12 and stiffens the toe portion of the shoe so as to resist knocks as well as retain its shape.

In carrying out the invention, I insert a cord 15' between the rear edge of the toe-box 15 and the cover 12, the cord thus being supported upon the comparatively stiff toe-box itself, so that the lining is not distorted in any manner so as to cause an uncomfortable pressure upon the wearer's foot. On the other hand, the cover 12 is distorted or raised by the cord 15' and conforms to the configuration of the latter with the resultant formation of a rib or bead 16 which appears on the exterior of the cover at the rear edge of the toe-box and reproduces somewhat the appearance of the usual ornamental seam at the tip of the toe of a shoe. The cover 12 passes as an integral unitary piece over the cord 15' as indicated.

To securely anchor the cord in place, it may be coated with rubber cement, as shown at 17, which coating will unite with the rubber stock in the rag stock toe-box 15 and form a firm bond between the cord 15' and the toe-box, which bond becomes permanently set or fixed during the vulcanizing step, to which the shoes of the character illustrated are subjected. Obviously, the rubber in the rag stock toe-box and the cord will enter the interstices of the fabric layers of the upper and during vulcanization will unite the layers, toe-box and the cord, together.

While I have illustrated and described my invention in connection with a composite fabric shoe having a rubber sole, the invention in its broadest aspect includes the incorporation of a transversely extending cord secured upon a relatively stiff toe-box of any character interpolated between layers of material of any character whatever, even leather, whereby the stiffness of the toe-box will prevent the cord from being depressed inwardly to the material annoyance and discomfiture of the wearer of the boot or shoe.

In addition to distorting the cover 12 so as to present a bead or rib, the cord 15' by being substantially inextensible will also prevent abnormal stretch of the upper at the

toe, and consequently coact with the toe-box in holding the toe permanently in shape.

Having described my invention, what I claim and desire to protect by Letters Patent is:

1. In a shoe, the combination with a sole and an upper having an outer and an inner layer of material, of a toe-box between the layers for reinforcing the toe portion of the upper having a bead extending transversely from and secured to its upper surface and underneath the material constituting the outer layer of the upper to give bead formation thereto, said toe-box being of stiff material relatively to the inner layer for preventing the bead from being depressed inwardly.

2. A shoe embodying a sole and an upper comprising a plurality of layers secured to aid sole, a toe-box inserted between and reinforcing said layers, said layers continuing across said toe-box as a unitary integral

structure, and a cord on said toe-box giving beaded formation to the outer layer of the upper, the layers of the upper, the toe-box 25 and the cord being bonded together by vulcanized rubber.

3. A shoe embodying a sole, an upper comprising a plurality of fabric layers secured to said sole, a toe-box formed of rag 30 stock inserted between and reinforcing said layers, said layers continuing across said toe-box as an integral structure, and a rubber treated cord on said toe-box giving beaded formation to the outer layer of the upper, 35 the rubber of the toe-box and cord forming a vulcanized rubber bond which unites the layers of the upper, the toe-box, and the cord together.

Signed at Naugatuck, county of New Haven and State of Connecticut, this 17th day of June, 1915.

J. E. TRAVER.
